United States Patent Office.

DAVID W. WRIGHT, OF NEW YORK, N. Y.

Letters Patent No. 66,547, dated July 9, 1867.

COMBINATION OF PAPER-WEIGHT AND PEN-WIPER.

The Schedule referred to in these Letters Patent and making part of the same.

TO ALL WHOM IT MAY CONCERN:

Be it known that I, DAVID W. WRIGHT, of New York, in the county of New York, and State of New York, have invented certain new and useful improvements in Combined Pen-Wipers and Paper-Weights; and I do hereby declare that the following is a full, clear, and exact description of the same, reference being had to the accompanying drawings which form part of this specification, in which the letters of reference correspond in all the figures.

My said improvements form a very simple and convenient paper-weight and pen-wiper combined, upon which a pen may be wiped without holding the wiper with one hand while the pen is being wiped with the other. By the paper-weight being attached to the wiper it is held in place by its own weight, thereby requiring the use of only one hand; the peculiar form of the wiper being such that the pen may be wiped upon either of its sides with the greatest facility; and when the wiping surface becomes too much soiled for further use, it may be easily removed, and a new one substituted in its place. The paper-weight being used to hold the paper being written upon, or being copied, insures the pen-wiper to be kept in a most convenient place, upon the top of the paper-weight.

To enable others to make and use my invention, I will proceed to describe the construction and operation of the same. In the drawings annexed—

Figure 1 is a perspective view of my invention, with the cloth-wiper D.

Figure 2 is a view of the band removed, with the points for holding it in place.

In the several drawings annexed, A represents a paper-weight, being made of cast metal, glass, or other suitable material, having recesses b b' in its top, with a base c. B is a metal band, having points or hooks e e' e'' e''', to hold the covering or wiper D, composed of cloth, down in the recesses b b', while the band B confines the edges of the same against the sides of the paper-weight. When the wiper D becomes too much soiled for further use, it is only necessary to remove the metal band, which releases the wiper, and a new one may be put on its place, and press down the metal band, and it is held in place ready for use. To wipe the pen it is only necessary to draw the convex side of the pen in the recesses b b', and the concave side of the pen upon the projections forming the recesses, and it is cleaned in a very expeditious manner.

Having thus described my invention, what I desire to secure by Letters Patent, is—

I claim a paper-weight and pen-wiper combined, constructed substantially in the manner as and for the purposes set forth.

D. W. WRIGHT.
